CLIFTON CHISHOLM, OF CLEVELAND, OHIO, ASSIGNOR TO THE AMERICAN MULTIGRAPH SALES COMPANY, OF CLEVELAND, OHIO, A CORPORATION OF OHIO.

WORK-EJECTING MECHANISM FOR PRINTING APPARATUS.

Application filed March 3, 1928. Serial No. 258,770.

This invention relates to mechanism acting automatically to discharge a printed product following the impression stroke. The invention is particularly well adapted 5 for embodiment in an addressing machine employing individual address plates and a manually operable platen. When so embodied, it includes a device carried by the platen arm and serving to engage the paper 10 on the printing stroke of such arm and remaining in engagement during a portion of the reverse stroke of the arm and at that period having a movement relative to the arm to eject the printed work. The invention 15 is hereinafter more fully described in connection with a preferred embodiment illustrated in the drawings.

Fig. 1 is a plan of an addressing machine embodied in my invention; Fig. 2 is a vertical transverse section of the same on the line 2-2 of Fig. 1; Figs. 3 and 4 are views of the platen arm and discharge control mechanism shown in Fig. 2, but in different positions; Fig. 5 is a front elevation of the ejecting mechanism in the position shown in Fig. 4; Fig. 6 is a detail in vertical section on the line 6-6 of Fig. 5; Fig. 7 is a perspective of the rocking frame carrying the paper engaging members; Fig. 8 is a perspective 30 of a bracket to which the rocking frame is pivoted; Fig. 9 is a side elevation of the lever and latch controlling the rocking frame, on a larger scale than the two preceding figures; Fig. 10 is an edge view of the parts shown in 35 Fig. 9.

In the embodiment shown in the drawings, 10 indicates the bed of frame of a flat-bed addressing machine. Extending transversely across this frame is a channel 11 along which the address plate may travel 40 from a magazine 12 to printing position, after which it is discharged at the left hand side of the machine.

A manually operated impression arm 20 is 45 shown in the drawings as pivoted to the bed at 21 adjacent the rear end of the arm, while at the forward end is an operating handle 22, and a short distance behind the handle is a platen 30 adjustably carried by the arm in 50 the usual manner. The impression arm 20 is normally maintained elevated as shown in Fig. 2, by a suitable spring or springs 25 attached to rear extensions of the arm. The

rear extension 26 is connected by a suitable system of linkage 27 with a reciprocating 55 slide 28 in the channel 11.

As the arm 20 is depressed to effect the printing, by means of a plate directly below the platen 30, the slide 28 is carried toward the right so that the bottom-most address 60 plate A, Figs. 1 and 2, may drop from the magazine 12 onto the slide in front of a shoulder thereon; then as the platen moves upwardly, the linkage mechanism described moves the slide toward the left carrying the 65 bottom-most plate from the magazine into position immediately at the left thereof. The same movement carries the plate which has just been printed from by the platen into a receptacle 29 at the extreme left of 70 the machine, and at the same time carries an intermediate plate which was standing at the left of the magazine into printing position beneath the platen.

It will be seen that the mechanism and 75 operation above described are well known in addressing machines, and such machines have frequently been employed with the envelopes or cards addressed thereby removed manually following each impression. It is 80 desirable however, to provide automatic means effecting the discharge and that is one of the purposes of the present invention. The card or envelope is placed by hand beneath the platen, if desired against a suitable 85 guide 15 carried by the bed, and remains in this position on the down stroke of the platen. With my ejecting mechanism, which will now be described, as the platen is beginning its upstroke, a suitable device carried by the impression arm and engaging the 90 printed envelope or card, suddenly moves forwardly and thus ejects the work from the machine.

As shown in the drawing, I have secured 95 rigidly to the operating arm 20 a suitable bracket 40 (shown detached in Fig. 8) which has a portion 41 resting on top of the arm, an upwardly extending ear 42 and a pair of downwardly extending ears 43, 44. 100 Pivoted at 51 to these downwardly extending ears is a rocking frame 50, shown detached in Fig. 7. This frame has an intermediate plate-like portion 52, the ends of which terminate in the side wings 54 by 105 which the frame is pivoted. The inter-

- mediate portion 52 is shown as flanged rearwardly at the top at 55 and as having rearwardly flanged ears 56 at the bottom. Slidably mounted in the ears 56 and the flange 55 are a pair of vertical plungers 60. Each plunger has at its lower end a sleeve-like head 61 in which is mounted a projecting soft rubber plug 62. A compression spring 65 surrounds the shank of each plunger and is compressed between the flange 55 and a washer 68 resting on a pin in the plunger. Accordingly, the plungers have a tendency to move downwardly until the pins and washers are stopped by engaging the ears 56 of the swinging frame.
- The swinging frame 50 is given a tendency to rock with its lower end toward the front by means of a spring 70 anchored at its lower end to a pin 71 on the swinging frame 20 and at its upper end to the rigid bracket 40. The movement in this direction however, is limited by an arm 57 extending rearwardly from the wings 53 and adapted to engage the upper surface of the rigid bracket 40.
- Movement in the opposite direction is limited by an arm 58 on the wings 53 which is adapted to engage the under surface of the overhanging portion 41 of the rigid bracket 40.
- Pivoted at 81 to the upstanding ear 42 of the rigid bracket 40 is a lever 80 shown detached in Figs. 9 and 10. The upper end of this lever is connected by a link 83 with a rigid standard 84 on a frame. Pivoted at 85 to the lever 80 (that is below the pivot of the lever) is an arm 90 which by means of a pair of ears 91 carries a slidable latch pin 92. This pin is normally pressed downwardly by the spring 93 surrounding the pin and compressed between the upper ear 91 and a collar 95 on the pin. The arm 90 is normally held against a pin 87 carried by lever 80 by means of a spring 97 anchored to the arm 90 and the lever 80. The swinging frame 50 carries a shoulder with which the latch pin 92 coacts, as hereinafter explained. This shoulder is shown as comprising a small bracket or a clip 59 rigidly attached to the wings 53 of the frame 50.
- The relatively stationary bracket 40 carries a downward shoulder with which the upper end of one of the plungers 60 may coact, as hereinafter explained. As shown in Figs. 5 and 6, this shoulder comprises a screw 45 adjustable in the plate portion 41 of the bracket 40 and locked in the desired position by a jamb nut 46.
- The position of rest of the parts above described is as shown in Fig. 2. In that case the impression arm 20 is held in its elevated position by the lifting springs 25 and the link 83 holds the lever 80 tipped forwardly so that the lower end of the latch pin 92 is at the rear of the shoulder 59 and free from it. The spring 70 holds the rock-

ing frame 50 in the position shown in Fig. 2, the stop arm 57 engaging the stationary bracket plate 41.

It will be observed that the link 83 is materially shorter than the distance between the pivot 21 of the impression arm and the pivot 81 of the lever 80, with the result that as the impression arm 20 is lowered, the upper end of the lever 80 is held back (traveling relatively rearwardly of the travel of its pivot 81) so that the lower end of the lever 80 carries the latch pin 92 forwardly into engagement with the shoulder 59, and thereby rocks the frame 50 into the position shown in Fig. 3. In this position, where the plungers 60 have become normal to the operation arm and stand parallel to the side of the platen, the movement is stopped by the arm 58 abutting the cross portion 41 of the bracket 40.

The above condition continues as the impression arm descends to effect the printing. Before the platen 30 engages the address plate A the plungers 60 will have engaged the card or envelope B, Fig. 4, resting on the bed of the machine. This stops the downward movement of the plungers but as the platen arm and platen continue their downward movement to print, the frame 50 moves downwardly with reference to the plungers and this brings one of the plungers behind the head of the screw 45 as shown in Figs. 5 and 6. This locks the rocking frame 50 to the stationary bracket 40 preventing any swinging of the rocking frame. Almost immediately after the above locking has taken place, the latch pin 92 clears the shoulder 59; that is to say, the linkage and parts are so proportioned that as the platen arm is moving downwardly from the position shown in Fig. 3 to the printing position, the lower end of the pin 92 is traveling relatively upwardly along the forward end of the shoulder 59 and just after the plunger 60 locks with the screw 45, the pin 92 snubs off of the end of the shoulder 59 and the parts come into the position shown in Fig. 4. This is the position at the instant the printing is effected.

Following the printing impression, the impression arm and platen rise under the influence of the spring 25. In this movement the head of the screw 45 prevents the frame 50 from swinging until after the platen has well cleared the paper, but when the platen has risen far enough above the paper for the frame 40 to have lifted enough for the screw 45 to clear the plunger 60, then the spring 70 suddenly swings the released frame 50 forwardly while the soft lower ends of the plungers 60 are in engagement with the envelope. The result is to snap the envelope forwardly and discharge it over the front of the machine.

Following the discharge of the envelope,

as the impression arm moves upwardly, the forward swing of the lever 80 caused by the 5 link 83 causes the lower end of the latch pin 92 which was directly above the shoulder 59 as shown in Fig. 4, to come down into engagement with the top of that shoulder then to travel rearwardly along such top until it passes off of the same at the right hand end thereof and thus by reason 10 of its spring 93, assumes the position shown in Fig. 3.

It will be seen from the above description that the action of my ejecting mechanism is to cause the ejecting plungers to 15 engage the envelope while the plungers are in their rearward position and just preceding the printing stroke, the plungers remaining in this position until after the impression; then, on the upstroke of the impression arm after the platen has freed 20 the envelope, the frame carrying the plungers is allowed to swing suddenly forwardly, thus discharging the envelope or printed card at the front of the machine.

25 I claim:

1. The combination of reciprocating member adapted to effect an impression, and a discharge device carried by such member and adapted to engage the face of an envelope or card and move while in such engagement to discharge the same.

2. In a work ejecting mechanism for printing apparatus, the combination of a reciprocating impression arm, a platen carried thereby, and an ejecting mechanism carried by said arm and adapted to eject the paper as the platen is moving toward 35 idle position.

3. In a work ejecting mechanism for printing apparatus, the combination of an impression arm, a platen carried thereby, an ejecting mechanism carried by said arm and adapted to engage the paper as the platen is coming into printing position, and means 40 for automatically moving the ejecting mechanism relative to the platen as the platen is moving to idle position.

4. In an apparatus of the character described, the combination of a movable member carrying a platen, an ejector carried by said member, said ejector being movably mounted in the member to enable it to engage the paper ahead of the platen engagement and continue such engagement during 50 the printing action and thereafter, and automatic means for moving the ejector after the printing impression and while the ejector is still in engagement with the article 55 printed.

60 5. The combination with means for printing an article, of an ejecting mechanism having an elastic surface adapted to engage the printed face of the article and means for moving said ejecting mechanism rela-

tive to the printing means following the 65 printing to discharge the article.

6. The combination of means for making a printing impression, an ejecting mechanism movably mounted and adapted to engage the face of the article, and means acting after the impression and during the contact described for giving the ejecting mechanism a partial rotation about an axis to 70 eject the article.

7. The combination of an impression arm, 75 a platen carried thereby, an ejecting mechanism movably mounted on the impression arm and adapted to engage the article before the impression and remain in contact with it during the impression and for a 80 short time thereafter, and means acting after the impression and during the contact described for giving the ejecting mechanism a partial rotation about an axis to eject the material.

8. The combination of an arm carrying a platen, a spring pressed ejecting mechanism slidably mounted on the arm, said ejecting mechanism being adapted to engage the paper in advance of the platen engagement 90 and continue in engagement with the paper until after the platen has effected the printing and is moving away from the paper, and means for then moving the ejecting 95 mechanism.

9. The combination of an arm carrying a platen, a spring pressed ejecting mechanism slidably mounted on the arm, said ejecting mechanism being adapted to engage the face of the paper, and means acting while the platen is moving away from 100 the paper, for then giving the ejecting mechanism a portion of a rotation about an axis to eject the printed article.

10. In an addressing machine, the combination with a frame, mechanism for moving a series of address plates along the same, a movable impression member adapted to 105 contact with an address plate to print an address on suitable material, an ejecting mechanism carried with the impression member adapted to engage the face of such material, and means for moving the ejecting mechanism relative to the impression member to eject such material.

11. In an addressing machine, the combination of a bed for supporting a series of address plates, a platen arm pivoted to the bed, a platen carried by the arm, an ejector 110 slidably carried by the platen arm and spring pressed downwardly, whereby the ejector may engage the paper before the platen and remain in contact therewith until after the platen has cleared the paper, and means for automatically moving the 120 ejector after the platen has cleared the paper to eject the printed article.

12. In an addressing machine, the combi-

- nation of an arm, a rockable frame carried by the arm, a slideable plunger mounted in said frame, a control mechanism for causing the plunger to engage the material to be ejected while the rockable frame is in one position and thereafter to move the rockable frame while the plunger is still in engagement with the article.
13. The combination of an impression arm, a platen carried thereby, a rockable frame carried by the impression arm, a plunger slidably mounted in the rockable frame, a spring for pressing the plunger downwardly but allowing it to move upwardly in the frame as the platen comes to printing action, a latch mechanism to hold the rockable frame in one position during the printing and thereafter release it, and a spring to give the frame a sudden movement when released to eject the printed article.
14. The combination of a pivoted arm, a platen carried thereby, a rockable frame carried by the arm, a plunger slidably mounted in the frame and spring pressed toward the printing plane, a lever carried by the platen arm, a latch carried by the lever and adapted to coact with the rockable frame to hold it in position or release it, and mechanism connected with the lever and adapted to control its operation.
15. The combination of a pivoted platen arm, a platen carried thereby, a rockable frame mounted on the arm, a slideable plunger mounted in the frame and spring pressed downwardly and adapted to engage the paper ahead of the platen and remain in engagement after the platen clears the paper on the upstroke of the arm, a latch mechanism adapted to hold the rockable frame in one position during engagement with the paper until after the printing, a linkage connection for controlling the plunger mechanism and releasing it after the printing, and means for causing such released plunger to take a sudden movement with the printed article to eject it.
16. The combination of a bed, a platen arm pivoted to the bed, a platen on the platen arm, a frame pivotally mounted on the platen arm, a plunger slidably mounted in the pivoted frame and adapted to engage the article being printed, a lever pivotally mounted on the platen arm and carrying a spring controlled latch for controlling the pivoted frame, a link connected to and adapted to automatically swing the lever, and a spring to move the released pivoted frame.
17. In an addressing machine, the combination of a platen arm, a platen carried thereby, a pivoted frame carried by the platen arm, a latch mechanism adapted to rock the pivoted frame, an ejecting plunger slidably mounted in the pivoted frame, and a spring pressed toward the paper being printed, said plunger having an elastic foot adapted to engage the face of the paper in advance of the printing and remain in engagement during the printing and until after the platen has cleared the paper, a lock for the pivoted frame, and means for causing said lock to be effective before the printing takes place and to release said lock after the controlling latch described has released the pivoted arm.
18. In an addressing machine, the combination of a bed, mechanism for feeding address plates along the same, a platen arm pivoted to the bed, a handle for operating the platen arm, means actuated upon the upstroke of the handle for operating the plate feeding mechanism, a platen on the platen arm, a frame pivotally mounted on the platen arm, a plunger slidably mounted in the pivoted frame and adapted to engage the face of the article being printed, a lever pivotally mounted on the platen arm and carrying a spring controlled latch for controlling the pivoted frame, a link connected at one end to the bed and at the other to the lever to retract the pivoted frame.
19. The combination of a movable member adapted to effect a printing impression, and a discharge device carried by such movable member and adapted to engage an envelope or card and means for moving said device relative to the member following the printing action, and while the member is in engagement with the envelope or card to discharge the same.
20. The combination with means for printing an article, of an ejector adapted to engage the face of the article before the printing impression and remain in contact with it during the impression and for a short time thereafter, and means for moving the ejector relative to the printing means after the impression and while the ejector is in contact with the article to discharge it.
- In testimony whereof, I hereunto affix my signature.

CLIFTON CHISHOLM.
